UNITED STATES PATENT OFFICE.

ROBERT M. FIGG, OF LE MARS, IOWA.

GOLD-CATCHING DENTAL-CUSPIDOR ATTACHMENT.

1,265,898.

Specification of Letters Patent. Patented May 14, 1918.

Application filed July 17, 1917. Serial No. 181,165.

To all whom it may concern:

Be it known that I, Dr. ROBERT M. FIGG, a citizen of the United States, and a resident of Le Mars, in the county of Plymouth 5 and State of Iowa, have invented certain new and useful Improvements in Gold-Catching Dental-Cuspidor Attachments, of which the following is a specification, reference being had to the accompanying drawings, forming a part of this specification.

This invention relates to certain new and useful improvements in dentists' spittoon attachments. The special object of the invention is to provide a device for saving the 10 gold particles.

Another object is to provide a simply constructed positively operating cuspidor attachment whereby the small gold particles removed in grinding and polishing gold 15 filled teeth may be saved.

With these and other objects in view the present invention consists in the combination and arrangement of parts as will be herein-after more fully described and finally pointed out in the appended claims, it being further understood that changes in the specific structure shown and described may be made within the scope of the claims without departing from the spirit of the invention.

In the accompanying drawings forming a part of this specification and in which like numerals of reference indicate similar parts in the several views:—

Figure 1 shows an elevational view with parts broken away of a gold catching device embodying my invention disclosing the same as attached to a dental fountain spittoon.

Fig. 2 is a section on line 2, 2 of Fig. 1.

Fig. 3 is a top view of one of the tray forming members.

In my present invention, I provide a simply constructed attachment arranged to be used in connection with a dental cuspidor 45 whereby the gold particles removed in grinding gold filled teeth which have heretofore been an entire loss, are saved.

In the accompanying drawing I show a gold catching device embodying my invention as attached to a fountain spittoon A, which is in connection with the usual water pipe 1.

My invention proper comprises a housing made of two tubular members both of equal 55 length which are secured by means of a pipe connection D, near one end, as shown in

Fig. 1, whereby these two tubular members are held in parallel spaced relation. In the use of the attachment these members are secured in superposed horizontal position, as shown in Fig. 2.

By means of a nipple b the upper tubular member B is secured to the neck a of the spittoon A.

The member B has both of its ends closed by means of suitable caps 2 and 3 while the lower member C has one end closed by means of the cap 4, the other end being secured to a pipe connection 5, in the form of a bend, to which is secured an ordinary S-trap 6 from which extends the over flow pipe.

Held within the upper tubular member B is a flat top base member 11 which snugly fits into the lower portion of the housing B as shown in Fig. 2 and removably held upon the top 11 is the gold catching tray-forming member 12 which member is provided with a plurality of transversely extending spaced grooves 14 between which are located groups of semi-circular depressions 15 which serve as wells in catching the gold particles as they are carried through the housing by means of the water escape in flushing the cuspidor.

The two members B and C with the connection D form a water way through which the gold carrying water passes in finding an escape to soil pipe.

The lower member C is provided with a simple flat member 10 closely fitting into what forms the bottom portion of the tubular member and removably held on this member 10 is the gold tray-forming member 13 also provided with a plurality of transverse grooves 14 and groups of semi-circular depressions 15.

The members B and C are secured in superposed horizontal spaced relation and held by means of a suitable bracket 9 which bracket is provided with the outwardly curved clasping portion 17 and upper clasping portion 16 used in conjunction with a yoke comprising an upper clasping portion 19 and lower clasping portion 20, this yoke being held to the bracket by means of the bolt 18 as shown in Fig. 2.

To remove the gold that settles within the wells and transverse grooves, it is simply necessary to remove the end caps 3 and 4 withdraw the trays and remove the collected precious metal.

Having thus described my said invention, what I claim as new and desire to secure by U. S. Letters Patent is:—

1. A gold catching device of the character described including a housing comprising two superposed tubular members held in spaced relation, said members being connected near one end, and said upper tubular member being arranged to be brought into connection with a dental spittoon, caps for closing the ends of said upper member, said lower member at one end being connected to an S-trap, a cap for closing the other end of said lower member, a flat top base member closely fitting into the bottom portion of each of said tubular members and a removable tray-forming member held upon each of said base members, each tray mem-

ber having a plurality of transverse grooves arranged in spaced relation, with a plurality 20 of semi-circular depressions between said grooves.

2. A dental spittoon attachment comprising two connected tubular members one of said members being adapted to be connected 25 to a dental cuspidor, the other member arranged to be connected to an S-trap, and a gold catching tray removably held within each of said tubular members, all arranged as and for the purpose set forth. 30

In testimony whereof I affix my signature in the presence of two witnesses.

ROBERT M. FIGG.

Witnesses:
